UNITED STATES PATENT OFFICE.

WILLIAM B. DOW, OF WILKES-BARRÉ, PENNSYLVANIA.

APPARATUS FOR STARCHING CLOTHES.

SPECIFICATION forming part of Letters Patent No. 512,282, dated January 9, 1894.

Application filed September 28, 1893. Serial No. 486,684. (No model.)

To all whom it may concern:

Be it known that I, WILLIAM B. Dow, a citizen of the United States, residing at Wilkes-Barre, in the county of Luzerne and State of Pennsylvania, have invented certain new and useful Improvements in Apparatus for Starching Clothes; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to that class of starching machines wherein the clothes to be starched are suspended in a starch receptacle and so arranged that no part other than that requiring the starch is subjected to its action.

20 Referring to the accompanying drawings for a complete disclosure of my invention: Figure 1 represents a perspective view of a complete machine; Fig. 2 a perspective view showing a detail; Fig. 3 a perspective view of 25 the pinion for holding the top of the machine together, and Fig. 4 a perspective view illustrating the manner of suspending the clothes.

The reference letter A indicates the hollow body of the machine which is rectangular in 30 shape and forms the starch receptacle. This body is supported upon the legs A' and the upper side is closed by the top B, which rests on the edges of the body, which is provided with a strip of packing material C to form a 35 tight joint.

Secured to the body A upon both sides thereof is the curved lever O, which has one end pivotally connected to a hook N which is in turn detachably connected to the top B by 40 means of a pin or stud thereon. Operating with the lever O is a cam lever P, which is arranged, when moved to the left, to engage the lever O and force it to turn on its pivot so as to clamp the top B down tightly on the body A and thus form a hermetic connection.

The top B is composed of two parallel side bars connected at one end by an end piece B' and provided with a raised portion b, by which the top may be lifted. Formed in each end 50 of the side bars on their inner sides, are longitudinal grooves c, which extend the entire length of the bars and receive the trunnions

of the rollers E and sliding block F. The rollers E are of a sufficient number to form, when in engagement, a closed top or cover, 55 while the block F is adapted to engage the extreme left-hand roller. By means of a rack G and pinion H, operated by a crank I, the block may be forced against the rollers and the latter made to closely press each other, 60 and close the top. The pinion H is mounted on a shaft H' which is in turn journaled in the arch J, while the rollers and block are prevented from receding by means of the pawl K² working in a vertical passage in the arch 65 J and adapted to engage with the teeth of the pinion H. Attached to the upper end of the pawl K² and operating to keep said pawl in engagement with the teeth of the pinion H, is a leaf spring K having its free end turned up 70 whereby it may be grasped and lifted to release the pawl K².

D indicates a steam pipe which passes through the side of and extends longitudinally within the bottom of the body A, and is 75 connected with the pipe D² which communicates with any suitable steam boiler, a valve d being employed to regulate the escape of steam.

L represents a plug whereby the starch may 80 be withdrawn from the body A.

Secured to the body A, at each end and on one side, are vertical standards M' to the upper ends of which a horizontal rod M is attached.

The preferred construction of my device having thus been set forth, I will now proceed to describe its mode of operation. The articles to be starched are hung from the bar M and so folded that only the parts to be starched, 90 such as the bosom, yoke, wrist-bands, and neck-band of the shirt, (see Fig. 4) will extend below and between the rollers E, and into the starch within the receptacle. The rollers E are now pressed tightly together by the 95 block F and rack and pinion G and H, thus gripping the clothes and forming a top sufficiently steam and air-tight for the purpose desired. The valve d is now opened and the steam from the boiler allowed to enter the 100 pipe D from whence it escapes through the openings in the pipe, thereby forcing the starch upward and saturating the clothes. After those parts of the clothes which are

within the body A have been saturated with the requisite amount of starch, they may be removed from the machine by relaxing the pressure against the rollers E sufficiently to 5 allow the clothes to be withdrawn. In the operation of withdrawal the pressure of the rollers will remove the superfluous starch, leaving the clothes in proper shape to be wiped and hung up.

10 It will be obvious that I am not limited to the use of the rollers E, in the top of the box, for they could readily be replaced by various other contrivances such as a series of independently movable blocks or bars operating 15 to open and close in grooves similar to those shown in the drawings.

Having thus described my invention, what I claim as new, and desire to secure by Letters Patent, is—

20 1. An apparatus for starching clothes, comprising a body portion, adapted to contain the starch and those portions of the clothes which are to be subjected to its action, a top for the

body portion, consisting of a frame to receive a series of laterally movable rollers, adapted 25 to have the clothes to be starched placed between them, means for pressing the said rollers in close engagement, whereby the top is closed and the clothes held securely, and a steam conveying pipe, arranged in the body 30 portion, whereby the starch is thrown against the clothes, substantially as described.

2. An apparatus for starching clothes, comprising a body portion adapted to contain the starch, a top for the body having a series of 35 independent sections movable horizontally and adapted to receive the clothes between them, and means in the body portion for agitating the starch, substantially as described.

In testimony whereof I affix my signature in 40 presence of two witnesses.

WILLIAM B. DOW.
